UNITED STATES PATENT OFFICE.

BENO J. GUNDLACH, OF BELLEVILLE, ILLINOIS.

APPARATUS FOR SHARPENING REAMERS.

Application filed October 20, 1922. Serial No. 595,812.

To all whom it may concern:

Be it known that I, BENO J. GUNDLACH, a citizen of the United States, residing at Belleville, Illinois, have invented a certain 5 new and useful Improvement in Apparatus for Sharpening Reamers, of which the following is a full, clear, and exact description, such as will enable others skilled in the art to which it appertains to make and use the 10 same.

This invention relates to an apparatus for sharpening reamers.

The main object of my invention is to provide a novel apparatus for sharpening 15 reamers that can be adjusted easily to adapt it to reamers of different lengths and of different diameters. Other objects and desirable features of my invention will be herein-after pointed out.

20 To this end I have devised a reamer sharpening apparatus which comprises a means for supporting a reamer, a honing device that is adapted to be rubbed over the edges or outer ends of the blades or flutes 25 of the reamer so as to restore the cutting edges of the blades to their original condition, and means for maintaining said honing device in such a position that it will bear squarely and evenly on the edges or end 30 surfaces of the blades of the reamer. The means that is used for supporting the reamer and preventing it from turning during the honing operation is constructed in such a way that it can be adjusted easily to adapt it 35 to reamers of different lengths and different diameters, and the supporting means for the honing device is constructed in such a way that it can be adjusted to adapt it to reamers of different diameters and lengths or to vary 40 the pitch or angle of the cutting edges of the reamer being honed.

Figure 1 of the drawings is a top plan view of a reamer sharpening apparatus constructed in accordance with my invention.

45 Figure 2 is a transverse sectional view, taken on the line 2—2 of Figure 1, looking in the direction indicated by the arrows; and

50 Figure 3 is a detail view, illustrating the kind of hone carrier that is used in case the reamer that is being sharpened has blades whose edges are slightly rounded.

55 Referring to the drawings which illustrate the preferred form of my invention, A and A' designate devices that are adapted to be used for holding a reamer α that is to

be sharpened, B designates a device that is adapted to be used for preventing the reamer from turning and for properly positioning the blades of the reamer, C designates a 60 hone secured to a hone carrier C' and adapted to be rubbed over the cutting edges γ of the blades of the reamer to sharpen the same, and D designates a support on which the hone carrier C' is adapted to be rested 65 when the hone C on said carrier is being rubbed over the cutting edges of the blades of the reamer. In the form of my invention herein illustrated the devices A and A' are 70 so constructed and arranged that they will hold the reamer α in a substantially horizontal position and the support D is so positioned that the hone carrier C' can be arranged at substantially right angles to the reamer with the hone C bearing upon the 75 center blade at the top side of the reamer, as shown in Figure 2.

The parts of the apparatus above described can be constructed in various ways without departing from the spirit of my 80 invention, but I prefer to adjustably mount either one or both of the devices A and A' on a stationary frame and mount the support D and the reamer holding device B on said frame in such a way that they can 85 be adjusted longitudinally of said frame and also raised and lowered relatively to said frame, as hereinafter described. In the form of my invention herein illustrated the stationary frame just referred to comprises a horizontally-disposed base piece 1, a pair of integral legs 2 arranged at one end of said base piece and a third leg 3 arranged at the opposite end of said base piece and adjustably connected to same in such a way 90 that it can be adjusted longitudinally of said base piece into any desired position and then locked in its adjusted position by a clamping means 4 that is shown in dotted lines in Figure 1. The reamer supporting 100 device A consists of a pointed device or substantially cone-shaped device mounted in a vertically-disposed arm 5 that projects upwardly from the base piece 1 to which said arm is integrally connected, and the 105 opposed reamer supporting device A' consists of a pointed or cone-shaped member carried by a screw 6 which passes through an internally screw-threaded hole in a bearing 7 on an arm 8 that is slidably mounted on the 110 base piece 1 in such a way that it can be adjusted longitudinally of same. The bear-

ing 7 is split and is provided with a screw 9 or the like that is adapted to be tightened so as to cause said bearing to clamp the screw 6 tightly enough to prevent it from 5 turning after the reamer has been clamped in operative position between the devices A and A'. Various means may be used for adjustably mounting the arm 8 on the base piece 1, but I prefer to make said base 10 piece substantially triangular-shaped in cross section, as shown in Figure 2, provide the arm 8 with a split portion that partially surrounds or embraces said base piece and equip said split portion with an adjusting 15 screw 10 and wing nut 10^a, as shown in Figure 1, that is adapted to be tightened so as to securely clamp the split portion of the arm 8 to the base piece 1, and thus retain the arm 8 in spaced relation with the arm 5 20 at the opposite end of the base piece 1. When the apparatus is being used for sharpening a long reamer, the wing nut 10^a is loosened so as to permit the arm 8 to be adjusted longitudinally of the base piece 1, 25 to the right, looking at Figure 1, said wing nut being tightened after the arm 8 has been adjusted into the proper position, so as to securely clamp said arm to the base piece 1. When a short reamer is to be 30 sharpened the arm 8 is adjusted longitudinally of the base piece 1, to the left, looking at Figure 1, so as to arrange said arm closer to the arm 5 which carries the reamer holding device A. The screw 6 on 35 which the device A' is mounted provides for a slight variation in the length of the space between the devices A and A', but the main function of said screw 6 is to clamp the reamer firmly between the devices A and A' 40 after the arm 8 has been adjusted in proper position on the base piece 1.

The support D for the hone carrier is 45 preferably pivotally connected at 11 to a bearing E that is slidingly mounted on the base piece 1, and means is provided for clamping said bearing to the base piece 1 and for adjusting the support D so as to change the elevation of the upper end of 50 said support on which the hone carrier C' rests. In the form of my invention herein 55 illustrated the bearing E is provided in its top side with a substantially V-shaped notch or groove that receives the base piece 1, as shown in Figure 2, and the means for clamping said bearing in adjusted position consists of a bolt 12 projecting downwardly 60 from the base piece 1 and provided with a wing nut 12^a that is adapted to be tightened so as to move the bearing E vertically with 65 relation to the base piece 1, thereby causing the substantially V-shaped base piece 1 to be drawn into snug engagement with the tapered walls of the groove in the top side of the bearing E which receives said base 70 piece. The base piece 1 is provided with

a longitudinally-disposed slot 13 of substantially T-shape in cross section in which the bolt 12 is arranged in such a manner that the head of same is positioned in the enlarged upper end portion of said slot, thereby permitting said bolt to slide longitudinally of the base piece 1 with the bearing E. If desired, the bearing E can be provided with a stiff spring 14, as shown in Figure 2, that laps over the top side of the base piece 1, and thus prevents said bearing from dropping downwardly out of engagement with the base piece 1 in the event the wing nut 12^a on the screw 12 is removed. 75

The device B previously referred to that is used for preventing the reamer from turning preferably consists of a flat blade that is slightly resilient and which is secured to a horizontally adjustable member 14 mounted 80 in the upper end of a vertically-adjustable member 15 which is arranged at one side of the base piece 1 in a laterally-projecting, bifurcated guide 16 on the bearing E. The member 15 is provided with an externally 85 screw-threaded shank 15^a and an adjusting nut 17 is mounted on said shank between the two portions of the bifurcated guide 16, the holes in the portions of the guide 16 through 90 which the shank 15^a passes being unthreaded. When the nut 17 is turned in one direction the member 15 will be moved upwardly, and when said nut 17 is turned in the opposite direction, said member will be moved downwardly. An adjusting screw 18 that passes 95 through an internally screw-threaded hole in the member 15 is used for moving the member 14 horizontally, and said member 14 is provided with a guiding device 19 having a horizontally-disposed portion that projects through a hole in the shank 15^a of the member 15, and thus prevents the member 14 from turning when the screw 18 on the member 14 is turned to change the position of 100 the device B. Turning of the screw-threaded shank 15^a relatively to the guide 16 through which said shank passes is prevented by means of a feather or spline 20 on said guide that projects into an elongated slot 21 in the shank 15^a that is shown in broken lines 105 in Figure 2. By adjusting the nut 17 the device B can be raised or lowered relatively to the reamer being sharpened, and by turning the swiveled screw 18 on the member 14 the device B can be moved towards and 110 away from the reamer or inwardly and outwardly with relation to the longitudinal axis of the reamer. 115

In using the apparatus a reamer y that is 120 to be sharpened is clamped in a substantially horizontal position between the devices A and A' by first setting the arm 8 in proper position on the base piece 1 and then manipulating the knurled finger piece 6^a of the screw 6, so as to cause the reamer to be held 125 130

securely between the devices A and A'. Thereafter, the nut 17 is turned in a direction to bring the member 14 into substantially parallel relation with the reamer, and the screw 18 is turned in a direction to cause the end of the device B to engage one of the blades or flutes of the reamer. The hone carrier C' is then arranged transversely of the reamer with the hone C bearing upon the center blade at the top side of the reamer, and the outer end portion of the hone carrier resting upon the upper end of the support D. If the hone does not bear squarely or evenly upon the flat end face of the blade on which the hone is resting, the support D can be raised or lowered by manipulating a screw 22 in a depending lug 23 on the support D that bears against the bearing E, or the same result can be accomplished by manipulating the screw 18 so as to cause the device B to exert pressure on the reamer and turn it into such a position that the hone will bear evenly on the particular blade of the reamer which the hone then engages. Thereafter, the nut 17 is turned in a direction to move the member 15 downwardly so as to place the device B under a slight tension, as shown in Figure 2. In the honing operation the hone carrier C' is moved forwardly and backwardly and also lengthwise of the reamer to a limited extent, so as to cause the hone to sharpen the cutting edges of the blades of the reamer, the hone carrier being operated either manually or by any suitable mechanical means. After one blade of the reamer has been sharpened, the nut 17 and screw 18 are manipulated so as to disengage the device B from the reamer and permit the reamer to be turned so as to bring another blade into operative position, after which the nut 17 and screw 18 are manipulated so as to cause the hone C to bear squarely on the next blade that is to be sharpened.

The particular shape or form of the hone carrier C' is immaterial, but I prefer to use a hone carrier that is provided with a relatively long handle and a portion 24 at the front end of said handle to which a hone C can be connected by screws or other suitable fastening devices 25, the support D for the hone carrier being provided in its upper end with a convexed bearing surface 26 on which the underside of the handle of the hone carrier C rests and a pair of upwardly-projecting ears 27 at the opposite ends of said bearing surface that prevent the handle of the hone carrier from slipping off the surface 26 during the honing operation. In the event the reamer being sharpened has cutting blades whose end faces are slightly rounded, as shown in Figure 3, it is desirable to use a hone carrier C² whose handle is provided on its underside with a concaved surface 28, as shown in Figure 3, so as to cause a slight rocking motion to be imparted to the hone,

and thus cause it to bear evenly on the rounded edge of the blade when the hone is moved back and forth over the blade.

It is possible with an apparatus of the construction above described to sharpen a reamer accurately without materially reducing the diameter of the reamer. Moreover, such an apparatus can be adjusted quickly to adapt it to reamers of different lengths and different diameters.

Having thus described my invention, what I claim as new and desire to secure by Letters Patent is:

1. A honing apparatus for reamers consisting of a frame provided with a base piece, means for maintaining a reamer in a substantially horizontal position, a member combined with said base piece, a vertically-adjustable honing device support carried by said member and arranged at one side of the reamer, and an adjustable reamer holding device on said member arranged in opposed relation to said honing device support.

2. A honing apparatus for reamers consisting of a frame provided with a base piece, an adjustable means for maintaining a reamer in a substantially horizontal position, a longitudinally-adjustable bearing on said base piece, a pivotally mounted, adjustable honing device support carried by said bearing, a reamer holding device on said bearing arranged in opposed relation to said honing device support, and means for enabling said reamer holding device to be raised and lowered and also adjusted towards and away from the reamer.

3. A honing apparatus for reamers consisting of a frame provided with a base piece, an adjustable means on said frame for maintaining a reamer in substantially parallel relation to said base piece, a longitudinally-adjustable bearing on said base piece, a support for a honing device projecting laterally from said bearing at one side of said base piece, means for raising and lowering said support, a reamer holding device arranged at the opposite side of said base piece, means for adjusting said holding device vertically relatively to said bearing, and means for adjusting said holding device towards and away from the longitudinal axis of the reamer.

4. A honing apparatus for reamers consisting of a frame provided with a base piece, adjustable elements on said frame between which a reamer can be positioned, a longitudinally adjustable bearing on said base piece, a support for a honing device pivotally mounted on said bearing, means for adjusting said support, a resilient holding device adapted to be moved into engagement with the reamer to prevent it from rotating, a horizontally-adjustable member to which said holding device is connected, and a vertically-adjustable supporting

means for said member carried by said bearing.

5. A honing apparatus for reamers consisting of a frame provided with a base piece, upright arms on said frame provided with members between which a reamer can be positioned, means for enabling one of said arms to be adjusted longitudinally of said base piece, a longitudinally-adjustable bearing on said base piece, a vertically-adjustable support on said bearing arranged at one side of the reamer and provided with a surface on which a honing device can be rested during the operation of honing the reamer, means for preventing the honing device from slipping off said surface, a resilient device that is adapted to be moved

into engagement with the reamer to prevent it from turning, and means for enabling said reamer holding device to be adjusted vertically and horizontally. 20

6. A honing apparatus for reamers, comprising means for holding a reamer in a substantially horizontal position, a support at one side of said reamer, a hone adapted to be rubbed over the portion of the reamer to be sharpened, and a carrier for said hone provided with a concaved surface that is adapted to ride upon said support during the honing operation whereby said carrier will be moved upwardly and downwardly 25 relatively to said support. 30

BENO J. GUNDLACH.
